UNITED STATES PATENT OFFICE.

GEORGE A. BOMANN, OF PLAINFIELD, NEW JERSEY.

DESIGN FOR PRINTED FABRIC OR SIMILAR ARTICLE.

Application filed August 25, 1923. Serial No. 7,089. Term of patent 3½ years.

To all whom it may concern:

Be it known that I, GEORGE A. BOMANN, a citizen of the United States of America, and residing at Plainfield, in the county of Union and State of New Jersey, have invented a new, original, and ornamental Design for Printed Fabric or Similar Article, of which the following is a specification, reference being had to the accompanying drawing, forming part thereof.

The figure is a plan view of a portion of printed fabric showing an embodiment of my new design.

I claim:

The ornamental design for printed fabric or similar article, as shown.

In testimony whereof I have signed my name to this specification.

GEORGE A. BOMANN.
